UNITED STATES PATENT OFFICE

STANLEY H. HINLEIN, OF ELKINS PARK, PENNSYLVANIA, ASSIGNOR TO J. H. HINLEIN & SONS, OF PHILADELPHIA, PENNSYLVANIA, A FIRM COMPOSED OF JOSEPH H. HINLEIN, MILTON J. HINLEIN, AND STANLEY H. HINLEIN

CHENILLE YARN

Application filed July 25, 1930. Serial No. 470,734.

This invention relates to chenille yarn, and the object of the invention is to provide a chenille yarn that will have an inherent relatively stiff resilient nature, by which raised patterns may be produced on fabric in which my improved yarn is used.

Chenille yarns of the prior art have been of a flaccid nature which, when incorporated in a fabric, lie flat and lifeless due to their having no inherent stiffness or resiliency. This lack of inherent resiliency and stiffness is due to the construction of the yarn, which usually is composed of a flaccid core thread, around which, in the uncut chenille yarn, the curled chenille thread is placed, the chenille thread being bound to the core thread by a flaccid binder thread twisted about the core thread and catching the chenille thread at various spaced intervals along the core thread to form the whole into the ultimate chenille yarn.

In cut chenille yarns, of the prior art, the filaments of which the chenille tufts are formed are bound into the yarn by twisting two flaccid core threads together with the chenille tufts interposed between them.

In order to provide the inherent stiffness and resiliency in my improved yarn, I incorporate in the yarn an additional core strand or strands, each of which has in itself an inherent stiffness and resiliency which, when my improved chenille yarn is incorporated in a cloth, causes the yarn to stand up intermediate the points at which it is tied into the fabric, whereby I am able to produce beautiful raised pattern effects. My invention is applicable to chenille yarns of both the cut and uncut varieties.

Referring to the drawings:

Fig. 1 is a side view of a piece of uncut chenille yarn made in accordance with the principles of my invention, the figure being drawn to an enlarged scale;

Fig. 2 is a cross-section taken on the line 2—2, Fig. 1;

Fig. 3 is a perspective view of a piece of cut chenille yarn made in accordance with the principles of my invention, and

Fig. 4 is a cross-section taken on the line 4—4, Fig. 3.

As shown in Figs. 1 and 2, the uncut chenille yarn includes a flaccid core thread 1, composed of ordinary fibrous material commonly used in the making of chenille yarns.

Twisted loosely with and running throughout the length of the flaccid core thread 1, I provide a relatively stiff but resilient core strand 2. This core strand is composed preferably of horse hair but it may be composed of any other natural or synthetic filament having the desired inherent stiffness and resiliency.

Around the core threads 1 and 2, I twist the usual chenille thread 3 which, as shown in Figs. 1 and 2, is composed of a plurality of relatively fine filaments grouped together, which in the aggregate produce a thread of a more or less spiral or curly nature, consisting of a series of successive convolutions 4 throughout its length. As this curled chenille thread is twisted loosely around the core strands 1 and 2 certain of the convolutions are distorted or straightened out, forming relatively straight portions 5 which lie against one side or the other of the core composed of the strands 1—2.

The chenille thread 3 is bound to the core member 1—2 by means of the usual flaccid binding thread 6 which combines with the core strands 1—2 as a part of the core in the finished yarn. As the binder thread is twisted around the other core strands 1—2 and around the curled chenille thread 3, it binds the said chenille thread to the core strands 1 and 2, flattening some of the natural curls in the chenille thread and thereby producing the relatively straight portions 5 therein.

The inherent stiffness produced in the chenille yarn by the presence of the horse hair or other stiff resilient strand 2 causes the yarn, when incorporated into a fabric and bound therein at spaced intervals throughout its length, to raise above the body of the fabric in a manner which produces the raised pattern effects on the fabric.

The chenille thread 3 is of the usual character consisting of a plurality of strands of relatively fine filaments of natural or synthetic silk, or other suitable material which

is capable of being formed into a series of curls or convolutions as it is twisted around the core members of the yarn or prior to its being twisted around said core members.

5 In Figs. 3 and 4, the cut chenille yarn is shown as being constructed of a pair of flaccid core members 1a, 1a twisted about or inter-twisted with a pair of relatively stiff inherently resilient core members 2a, 2a, composed of horse hair or other suitable material of the 10 character above noted.

The chenille thread in this case, in place of being curled and twisted loosely around the core elements is passed back and forth between pairs of the core elements, a flaccid core strand 1a and a resilient core strand 2a comprising one of said pairs and the other core elements 1a and 2a comprising the second of said pairs, the outer loops of the chenille thread 3a thereafter being cut in the usual 20 manner producing tufts 4a, held between the said pairs of core elements 1a—2a and 1a—2a, as clearly shown in Fig. 4. The tufts are placed one against the other or in such relatively close relationship to each other as to 25 form a substantially cylindrical cut surface on the outside of the yarn, as illustrated in Figs. 3 and 4.

The yarn shown in Figs. 3 and 4, like that 30 shown in Figs. 1 and 2, when incorporated in a fabric, will stand up from the foundation of the fabric producing the raised pattern effects above noted, varying from the above mentioned uncut chenille fabric only 35 in that its appearance is different to the same extent as any cut chenille fabric differs from an uncut chenille fabric of the same general character or design.

The two general types of chenille yarn to 40 which my invention is particularly adaptable have been referred to throughout the specification as "cut" and "uncut" chenille. The "cut" type is usually referred to in the trade as "chenille", while the "uncut" type is frequently referred to as "frill" yarn or "ratine" 45 for the purpose of distinction.

I claim:

1. A chenille yarn characterized by the presence therein of a relatively stiff resilient core.
- 50 2. A chenille yarn characterized by the presence therein of a core strand having an inherent relatively stiff resilient nature.
3. A chenille yarn characterized by the presence therein of a plurality of inherently 55 stiff resilient core strands.
4. A chenille yarn characterized by the presence therein of a core composed of a plurality of individual strands, at least one of 60 which has an inherently stiff resilient nature.
5. A chenille yarn characterized by the presence therein of a core composed of a plurality of individual strands twisted together, 65 at least one of which has an inherently stiff

resilient nature, and a plurality of relatively fine filaments surrounding said core and bound thereto.

6. A chenille yarn characterized by the presence therein of a core composed of a plurality of individual strands twisted together, at least one of which has an inherently stiff 70 resilient nature, and a plurality of relatively fine filaments grouped together and extending laterally from and secured to said core.

7. A chenille yarn comprising a plurality of relatively flaccid core strands and a relatively stiff resilient core strand twisted together, and a plurality of filaments grouped together and bound to the core by the inter-twisting of the strands thereof. 75

8. A chenille yarn comprising a plurality of relatively flaccid core strands and a relatively stiff resilient core strand twisted together, and a plurality of filaments grouped together and twisted loosely around the core and bound to the core by the inter-twisting 80 of the strands thereof.

9. A chenille yarn comprising a flaccid core strand and a core strand having an inherent relatively stiff resilient nature, a chenille thread comprising a plurality of relatively fine filaments grouped together and twisted in a relatively loose manner about said core, and a binder thread twisted around the core and the chenille thread to bind the latter to the former. 90

10. A chenille yarn comprising a flaccid core strand and a core strand having an inherent relatively stiff resilient nature, a chenille thread comprising a plurality of relatively fine filaments grouped together and twisted to produce therein a series of convolutions, said curled thread being twisted in a relatively loose manner about said core, and a binder thread twisted around the core and the chenille thread to bind the latter to the former. 100

11. A chenille yarn comprising a plurality of relatively flaccid core strands and a plurality of relatively stiff core strands twisted together, and a plurality of filaments extending substantially radially from the core and bound thereto by the said inter-twisting of the core strands. 110

12. A chenille yarn comprising a plurality of relatively flaccid core strands and a plurality of relatively stiff core strands twisted together, and a plurality of filaments extending through the core between pairs of said core strands consisting respectively of a flaccid strand and a relatively stiff strand, said filaments extending substantially radially from the core and bound thereto by the said inter-twisting of the core strands. 120

13. A chenille yarn characterized by the presence therein of a core strand composed of horse hair. 125

STANLEY H. HINLEIN.
